UNITED STATES PATENT OFFICE.

JAMES B. LUND, OF CHICAGO, ILLINOIS.

ATTACHMENT FOR CARBURETERS.

1,017,572.

Specification of Letters Patent.

Patented Feb. 13, 1912.

Application filed December 18, 1911. Serial No. 666,814.

To all whom it may concern:

Be it known that I, JAMES B. LUND, a citizen of the United States, and resident of Chicago, in the county of Cook and State of Illinois, have invented certain new and useful Improvements in Attachments for Carbureters, of which the following is a specification.

This invention relates to carbureter attachments and aims to provide means whereby the temperature of the gas delivered from the carbureter to the engine cylinders is automatically controlled.

It is well known that gas engines will run most smoothly and efficiently when the mixture delivered to the cylinders is of uniform temperature but prior to my invention the temperature of the mixture has varied within wide limits with variations in the speed of the engine and in the atmospheric conditions.

It is the object of my present invention to maintain a uniform temperature of the mixture delivered to the engine cylinders and this result is accomplished by providing two air intakes for the carbureter, one for hot air and the other for cold and controlling the proportions of air admitted through each opening by an element sensitive to both temperature and pressure located in the mixture pipe between the carbureter and the engine.

My invention will be best understood by reference to the following description when considered in connection with the accompanying drawings illustrating one preferred form of the invention.

Referring to the drawings—Figure 1 is a side elevation partially in section of a carbureter equipped with my invention. Fig. 2 is a plan view of my improved air heating device, a portion of the shell being broken away; and Fig. 3 is a sectional view taken on the line 3—3 of Fig. 1.

On the drawings 8 designates a carbureter of any well known or preferred type equipped with the usual throttle valve 9 adapted to be controlled in the usual way by the driver through the instrumentality of the connecting rod 10. The air is delivered to the carbureter through an air supply pipe 11 connected at its intake with a heater. This heater as shown in Fig. 2 preferably comprises a section of pipe 13 interposed in the exhaust pipe 14 from the engine and having a drum 15 surrounding the section

and connected therewith at intervals by radial ribs or partitions 16. The drum and the compartments formed by the partitions are open at each end to permit the entrance of air into the compartments and the partitions are cut away at their central portions to leave a central chamber surrounding the pipe 13 and communicating with the air supply pipe 11. The air which is drawn into the heater at both ends thereof is heated by the pipe 13 and the radial partitions 16 to a relatively high temperature before it is delivered to the carbureter through the supply pipe 11.

The supply pipe is preferably squared throughout a portion of its length and this squared portion is provided with a port 17 communicating directly with the atmosphere. A shutter 18 hinged at 19 adjacent one side of the port is adapted, when in elevated position, to close the port and when in lowered position to close the pipe 11 between the port and the heater. It will be manifest that when the shutter is partially open or in intermediate position air will be drawn into the carbureter both directly from the atmosphere through the port 17 and also through the heater 12. By regulating the position of the shutter the proper proportions of hot and cold air will be admitted through the heater and the port 17, respectively, to produce a mixture of air of the proper temperature to give most satisfactory results in the carbureter and deliver a mixture to the cylinders of a required predetermined temperature.

As shown in Fig. 1 the pipe leading from the carbureter to the manifold 20 connected with the engine cylinders in the usual way is enlarged as indicated at 21 to accommodate a pressure and temperature controlled element 22. While I do not desire to limit the invention to an element of any particular construction I have illustrated on the drawings a practical type of element comprising a closed cylinder filled with an expansible fluid, the walls of said cylinder being of accordion construction to permit expansion and contraction of the element in a longitudinal direction. The element 22 is adapted to expand upon reduction of the external pressure thereon and under the influence of heat and to contract under the influence of an increased external pressure or a decrease in temperature. A bearing 23 projects laterally from the side of the en-

larged section of pipe 21 and in this bearing is slidably mounted a link or rod 24 attached at its inner end to the free end of the element 22 and at its outer end to one arm of a bell-crank lever 25 pivotally mounted upon a suitable stationary bracket 26. The other arm of the bell-crank lever 25 is connected by a link 27 with the shutter 18. The rod 24 is preferably provided with a joint 28 to permit movements of its outer end in an arc defined by the bell-crank lever and the length of the rod may be regulated to secure the proper adjustment between the element 22 and the shutter by means of a turn-buckle connection 29. It will be evident that as the element 22 expands, either by reason of a rise in temperature of the mixture delivered from the carbureter or by reason of increased vacuum in the pipe caused by throttling the engine, the shutter 18 will be moved toward the dotted line position shown in Fig. 1 to decrease the supply of heated air drawn in through the heater 12 and increase the supply of cool air drawn directly from the atmosphere through the port 17. Thus it will be seen that by accurately regulating the position of the shutter 18 the temperature of the mixture delivered by the carbureter is automatically controlled and the most efficient explosive mixture is delivered at all times to the engine.

It has been determined that the most satisfactory and efficient operation of an engine can be obtained when the mixture is delivered to the cylinders at a temperature ranging between 95 and 100° F. When the engine is running under ordinary conditions with the throttle open about 35° of heat is expended in the carbureter in evaporating the gasoline, consequently there is a difference in temperature of about 35° between the air in the pipe 11 before it enters the carbureter and the mixture in the pipe 21 delivered from the carbureter. It is, therefore, desirable to maintain the air in the intake pipe at a temperature of about 130° to 135° F. In assembling the device the various parts are so adjusted that under ordinary atmospheric pressure a temperature slightly above 100° will be maintained in the pipe 21. In actual operation, however, the pressure in the pipe 21 is always slightly below atmospheric pressure even when the engine is running with the throttle wide open and the expansion of the element 22 caused by this decrease in pressure will cause the shutter to close the hot air inlet sufficiently to maintain a running temperature around the element at a point between 95° and 100°. So long as the throttle remains open the thermostatic action of the element 22 will maintain a substantially uniform temperature of the mixture being delivered to the cylinders.

When the engine is running with the

throttle partially or nearly closed, however, the pressure around the element will be decreased or, in other words, the vacuum will be increased. The decrease in pressure will, of course, cause the element to expand thereby shutting down the supply of heated air from the heater 12. This action would tend to reduce the temperature of the mixture beyond the required amounts were it not for the fact that when the throttle is closed the vacuum below the throttle or in the carbureter is decreased and the air in the carbureter being under greater pressure will vaporize a correspondingly smaller amount of liquid and lose a proportionately less number of heat units in the act of vaporization. The result is that the mixture delivered to the cylinder is of the proper temperature. It is a well known fact that there is a tendency for the carbureter to flood when the engine is throttled and, with carbureters not equipped with my invention, when the throttle is suddenly opened a considerable quantity of gasoline poorly and inadequately vaporized is sucked directly into the cylinder thereby causing ragged explosions and a dense smoke heavily laden with carbon to issue from the exhaust. With my present invention, however, when the throttle is suddenly opened the pressure in the chamber 21 surrounding the element will immediately rise to approximately atmospheric pressure. This increase of pressure will cause the element to instantaneously contract so as to throw the shutter 19 over the cold air port 17 thereby admitting highly heated air to the carbureter. This highly heated air, the temperature of which is above that normally required, will lose a considerable portion of its heat in vaporizing the excess gasoline which has accumulated in the carbureter while the engine was throttled and when this air reaches the cylinders it will be found to be of approximately the desired temperature. This sudden influx of hot air when the throttle is opened is of great importance in that the highly heated air will quickly evaporate the excess or accumulation of gasoline in the flooded carbureter thereby preventing the gasoline from being drawn into the cylinders in a poorly vaporized condition. The result is that the engine will pick up without any ragged or imperfect explosions and without producing a heavy carbon laden exhaust. As soon as the excess of gasoline in the carbureter has been evaporated the temperature of the mixture delivered to the manifold will rise, whereupon the element 22 will expand under the influence of the heated mixture and open the cold air port sufficiently to properly regulate the temperature of the air delivered to the carbureter. So long as the position of the throttle remains unchanged the pressure around the

element will remain practically constant and the temperature of the mixture will be controlled thermostatically from the element 22.

From the foregoing it will be manifest that the temperature of the mixture delivered to the cylinders is controlled thermostatically from the element 22 so long as the throttle remains in one position and the pressure around the element consequently remains constant but that, when the throttle is suddenly closed or suddenly opened, the variations in pressure in the pipe 21 will actuate the element 22 to assist in maintaining a predetermined temperature.

While I have shown and described in detail the embodiments of my invention which appear, at the present time, to be most desirable, it will be apparent that various changes in the shape, construction and arrangement of the various parts may be resorted to without departing from the spirit or sacrificing any of the material advantages of the invention.

The subject-matter which is disclosed in this application and not claimed therein, to wit: the thermostatic regulation alone, forms the subject-matter of my copending application, Serial No. 636,833, filed July 5, 1911.

I claim:

1. The combination of a carbureter, a pipe adapted to connect said carbureter with an engine manifold, and means adapted to be actuated by temperature and pressure for automatically regulating the temperature of the mixture delivered from said carbureter through said pipe.

2. The combination of a carbureter, an air intake pipe connected therewith, a shutter disposed in said pipe for controlling the relative proportions of hot and cold air delivered to said carbureter, and means actuated by variations in temperature and pressure for automatically controlling the operation of said shutter.

3. The combination of a carbureter, an air intake pipe connected therewith and provided with a cold air inlet port, means for heating the air drawn into the end of said pipe, and temperature and pressure controlled means for automatically regulating the proportions of hot and cold air ad-

mitted to said pipe whereby to control the temperature of the mixture delivered from said carbureter.

55

4. The combination of a carbureter, an air intake pipe connected therewith and provided with a cold air port, an air heating device connected with said pipe, a shutter adapted to vary the relative proportions of air admitted through said heating device and through said port, and a heat and pressure controlled device for automatically controlling the operation of said shutter to regulate the temperature of the mixture delivered from said carbureter.

5. The combination of a carbureter, an air supply pipe therefor provided with a port communicating directly with the atmosphere, an air heating device attached to the end of said pipe, and thermostatically and pressure controlled means positioned to be influenced by the temperature and pressure of the mixture delivered from said carbureter whereby the temperature of said mixture may be automatically regulated.

6. The combination of a carbureter, a pipe for supplying air thereto, said pipe having a plurality of air inlet passages, one of said passages communicating directly with the atmosphere and another with an air heating device, a shutter mounted to control the proportions of cool and heated air drawn into said pipe, and a thermostatic device adapted to be actuated by temperature and pressure variations connected with said shutter for automatically controlling the operation of the shutter.

7. The combination of a carbureter, a pipe for supplying air thereto provided with cool and hot air inlet passages, a pressure and temperature controlled device located in the path of the mixture delivered from said carbureter, and means operated by said device for regulating the relative proportions of hot and cool air admitted to said pipe whereby to automatically control the temperature of the mixture delivered by the carbureter.
